UNITED STATES PATENT OFFICE.

ALBEN E. LUNDELL, OF NEW YORK, N. Y., ASSIGNOR TO WESTERN ELECTRIC COMPANY,
INCORPORATED, OF NEW YORK, N. Y., A CORPORATION OF NEW YORK.

TELEPHONE-EXCHANGE SYSTEM.

1,271,336.

Specification of Letters Patent. Patented July 2, 1918.

Application filed November 14, 1916. Serial No. 131,202.

To all whom it may concern:

Be it known that I, ALBEN E. LUNDELL, a citizen of the United States, residing at New York, in the county of Bronx and State 5 of New York, have invented certain new and useful Improvements in Telephone-Exchange Systems, of which the following is a full, clear, concise, and exact description.

This invention relates to an indicating arrangement adapted to be employed in telephone exchange systems for the purpose of visually indicating the number of a telephone line to an operator.

The object of the invention is to provide 15 an indicating arrangement which may be controlled from a distant point by means of a manually operable device, such as a set of keys, and which will cause the visual indication, at an operator's position, of the 20 number in accordance with which such manually operated device was set.

It is an object of the invention to provide 25 an arrangement of this character which will operate in a reliable manner, which will involve the use of a comparatively small amount of apparatus, and which may perform its function in a small interval of time.

In accordance with a feature of the invention an indicator is provided in which the 30 indication of a number of several digits may be accomplished by means of a plurality of relays which are adapted to be operated in various combinations in response to currents varying in character. In accordance with 35 such feature of the invention these relays are, by means of suitable impedances included in series therewith, arranged to respond to currents of different characters. Thus relays are provided which are tuned 40 to respond to frequencies of 66, 50, 33 and 16 cycles per second, and also relays which are adapted to respond only to direct current.

In accordance with a further feature of 45 the invention, the indicator relays are less in number than the number indicators controlled thereby, there being ten number indicators for each digit of the number, any one of which may be actuated upon the 50 operation of one of a set of five relays and one of a set of two relays. By virtue of this arrangement it is only necessary to employ currents of five different characters to select any one of ten number indicators.

55 Further features of the invention not spe-

cifically referred to above will appear from the detailed specification and the claims.

These and other features of the invention will be more readily understood by reference to the accompanying drawing in which: 60

Figures 1, 2, 3 and 4, when arranged with Fig. 2 below Fig. 1, Fig. 3 to the right of Fig. 1, and Fig. 4 below Fig. 3, show diagrammatically a trunk circuit extending between an A and B operators' positions together with an indicating arrangement embodying the principle of the invention. 65

When the calling subscriber removes the receiver from its switchhook in initiating a call, the line relay 1 is energized and 70 closes at its armature and contact a circuit for the line lamp 2. The operator, observing the line lamp 2, inserts the plug 3 into the jack 4. As soon as the plug has been placed in the jack, a circuit is established 75 for the relays 5 and 6, which may be traced from battery, through the relay 5, sleeve contact of the jack, cut-off relay 6, to ground. The relay 5 closes at its front contact a circuit for the motor magnet of sequence switch 80 7 which may be traced from battery, through the motor magnet of sequence switch 7, sequence switch contact 8 in position 1, front contact and armature of relay 5, to ground: whereupon the sequence switch 7 moves into 85 position 2. In position 2 the sequence switch contact 9 is closed and at its lower right contact establishes a circuit for the sender sequence switch 100, which may be traced from battery, through the motor magnet of 90 sequence switch 100, sequence switch contact 101 in position 1, conductor 102, sequence switch contact 9 in position 2, to ground. Sequence switch 100 thereupon moves into position 2. In position 2 of the 95 sequence switch 100, a circuit is established for the updrive magnet 103 of the cord finder, from battery, through such updrive magnet, sequence switch contact 104 in position 2, back contact and armature of relay 100 105, to ground. The energization of the updrive magnet causes the movable contact brushes of the cord finder, indicated at 106, 107, 108, 109 and 106^a, to pass over stationary terminals, one set of which are indicated at 110, 111, 112, 113 and 113^a, the set of stationary contacts shown being those which are associated with the particular cord which, it has been assumed, has been 106 taken for use in answering the particular 110

- call being described. As soon as the brush 109 makes contact with the contact 113, as there is a ground placed on such contact through the sequence switch contact 9 in position 2, the relay 105 is energized over a circuit which may be traced from battery, through relay 105, contact spring 114 in position 2, brush 109, contact 110, sequence switch contact 9 in position 2, to ground.
- 10 The relay 105 closes at its right-hand armature and front contact a circuit for the sequence switch 100 from battery, through the motor magnet of such sequence switch, contact 101 in position 2, front contact and right-hand armature of relay 105, to ground; whereupon sequence switch 100 moves into position 3. The relay 105, however, remains energized after the sequence switch 100 leaves position 2, as at its left-hand armature and contact a substitute circuit for such relay is closed through the sequence switch contact 114 in positions 2 to 16 and by way of brush 108, contact 111 and sequence switch contact 9 in positions 2 to 11 to ground.
- 15 The relay 105, when energized, also opens the energizing circuit previously traced for the updrive magnet 103, and thus stops the cord finder with the movable brushes thereof in contact with the set of stationary terminals individual to the cord shown in Fig. 1.
- 20 The operator, having ascertained the number desired from the calling subscriber, depresses the keys of the sending device, which has been associated with the cord, in accordance with the number of the desired line. There may be provided ten office, ten thousands, ten tens, ten units, and one starting key in the operator's sending device. These keys when depressed are mechanically 25 locked and are released by means of suitable release magnets. However, only one key of each set is indicated on the drawing, it being assumed that the number 0 office key indicated at 115 is depressed, the number 30 5 thousands key indicated at 116, the number 9 hundreds key indicated at 117, the number 3 tens key indicated at 118, and the number 0 units key indicated at 119; it being assumed, therefore, that the number desired is 05930. Having depressed the number keys, the operator thereupon depresses the starting key indicated at 120.

35 As soon as the starting key 120 is depressed a circuit is established for the office register indicated at 121, thousands register indicated at 122, hundreds register indicated at 123, tens register indicated at 124 and units register indicated at 125. This energizing circuit may be traced from battery, 40 through the various motor magnets of the registers, and thence through the right-hand armature and back contact of the cut-off relays individual to such registers, through the starting key 120, to ground. As soon as the 45 office register reaches position 0, a circuit is

closed for the office register cut-off relay indicated at 126, from battery, through the relay 127, cut-off relay 126, contact 173 of the register which is closed in position 0, key 115, to ground. Similarly, when the 70 thousands register reaches position 5, a circuit is established for the thousands cut-off relay indicated at 128, through the register spring 129 in position 5; a circuit is established for the hundreds register cut-off relay indicated at 130 through the register spring 131 in position 9; a circuit is established for the tens cut-off relay 132 through register contact 133 in position 3; and, finally, a circuit is established for the units 80 cut-off relay indicated at 134 through contact 135 in position zero. Each of these register cut-off relays, when operated, opens the energizing circuit for the corresponding register magnet and stops the registers in 85 the position corresponding to that designated by the depressed key. When all of the register cut-off magnets have operated, a series circuit is established for the sequence switch 100, which may be traced from battery, through the motor magnet of sequence switch 100, sequence switch contact 136 in position 3, left armatures and front contacts of the register cut-off relays 126, 128, 130, 132 and 134, to ground; whereupon the 90 sequence switch 100 moves from position 3 into position 5. As the sequence switch 100 reaches position 4, the relay 105 still being energized, a circuit is closed for the release magnets of the various keys, which cause 100 such release magnets to operate and restore the depressed keys to normal. This circuit may be traced from battery in parallel through the release magnets 137, 138, 139, 140, 141, 142, through the sequence switch contact 143 in position 4, to the right armature and front contact of relay 105, and ground. It will be observed that the relay 127 was energized when the registers were set; therefore, if all of the depressed keys are 105 completely restored when the sequence switch 100 passes position 4, the relay 127 will become deenergized and the sequence switch 100 will not stop in position 5 but will be driven out of position 5 over a circuit which 110 may be traced from battery, through the motormagnet of sequence switch 100, contact 136 in position 5, back contact and armature of relay 127. If the keys have not been restored, however, the sequence 115 switch 100 will wait in position 5 until the relay 127 becomes deenergized. Assuming, however, that the keys were restored by the operation of the release magnets, the sequence switch 100 moves into position 6, in 120 which position the fundamental circuit to the first selector switch, or, in this particular system disclosed, the office selector, is established. Included in the fundamental circuit and associated with the sender is the 125 130

usual stepping relay 144, and such fundamental circuit also includes at the office selector the usual line relay (not shown). The office selector is merely indicated diagrammatically by the brushes 10, 11 and 12, and a set of stationary contacts 13, 14, and 15. This selector may be of any well-known type but is preferably of the type disclosed in the applicant's Patent No. 1,168,819, and is 5 adapted to be driven by a suitable mechanism over sets of stationary terminals to select a set of terminals individual to a trunk leading to a B operator's position. Such switches are provided with an interrupting device which is adapted, as the switch brushes move from terminal to terminal, to intermittently shunt and deenergize the stepping relay 144. A set of counting relays, usually twenty in number, which are 10 also of well-known construction, is provided with each sending outfit, the number 0 or last pair of such relays being indicated in Fig. 2 at 145 and 146. However, as in the case assumed, the number zero office key having been depressed, it is only necessary that the office selector should take one step to bring the brushes thereof in contact with the trunks leading to the desired office. Only the last pair or No. 0 set is illustrated. 15 Therefore, as soon as sequence switch 100 reaches position 6 and the fundamental circuit is established, the stepping relay 144 becomes energized, and the counting relay 146 is energized over a circuit including the 20 office register spring 147 which is, as indicated, in position 0. This circuit may be traced from battery, through counting relay 146, register contact 147, armature and front contact of 144 to ground. As soon as relay 25 146 is energized it closes a locking circuit for itself including counting relay 145. This circuit may be traced from battery, through relay 146, armature and front contact thereof, relay 145, sequence switch 30 149 in position 6, to ground. Relay 145 is not operated in this circuit as it is short-circuited by the ground at the front contact of relay 144. When relay 144 is shunted in the well-known manner by the 35 interrupter at the selector switch, relay 145 is operated and opens the fundamental circuit at its left-hand armature and contact; thus opening the circuit of the line relay at the first office selector switch, stopping 40 said selector switch, and also closing at its right-hand armature and contact a circuit through sequence switch contact 136 for the sequence switch 100 when the sequence switch 7 has reached position 11, to drive 45 said sequence switch out of position 6, from which position it continues to rotate until position 17 is reached. When the selector switch is stopped, sequence switch 7 has, by means of circuits not shown, been driven to 50 position 11, the intermediate positions of 55 said sequence switch between 2 and 11 serving to control the operation of the selector switch. When the sequence switch 7 reaches position 11, a circuit is established from battery, motor magnet of sequence switch 100, 70 sequence switch contact 136, position 6, right armature and front contact of relay 145, brush 106^a, terminal 113^a, sequence switch contact 25 in position 11, to ground. The sequence switch 100 thereupon leaves position 6 and moves to position 18. In positions 7, 9, 11, 13, 15 and 17 of sequence switch 100, and in position 11 of the sequence switch 7, ground is placed upon one side of the trunk through the sequence switch contact 150, and a source of potential of a frequency determined by the set position of registers is placed on the other side of the trunk through sequence switch contacts 151 and 152. 75 80 85

Included in the trunk extending to the B operator's position is a step-by-step switch indicated at 300 and provided with two arms 301 and 302. This switch is adapted to be stepped around in response to the energization and deenergization of the motor magnet 303 through a pawl and ratchet mechanism operated by such motor magnet, the arrangement being such that when the magnet 303 is energized, the pawl is moved 90 over the teeth of the ratchet and when the magnet is deenergized the arms 301 and 302 are stepped forward one step by means of a spring acting upon the armature of such motor magnet. Associated with the lower 100 set of six contacts of such switch are conductors 304, 305, 306, 307, 308 and 309 leading to six sets of relays which when energized in certain combinations cause the display of 105 certain indicator lamps designated thousands indicator, hundreds indicator, tens indicator, and units indicator respectively. All of the upper set of contacts of the switch are connected together and to a conductor 110 310 to which is connected one side of one winding of each of the indicator relays. The relays 404, 409, 418 and 423 are tuned to respond to alternating current of 66 cycles; 115 relays 400, 405, 410, 414, 419 and 424 are tuned to respond to alternating current of 50 cycles; relays 401, 406, 411, 415, 420 and 425 are tuned to respond to alternating current of 33 cycles; relays 402, 407, 412, 416, 421 and 426 are tuned to respond to alternating current of 16 cycles; and relays 403, 120 408, 413, 417, 422 and 427 respond only to direct current. These relays may be tuned in any suitable manner and, as shown, such tuning is accomplished by means of condensers of various sizes indicated generally at 430. Each of the indicator relays is provided with a locking winding the arrangement being such that when any relay is 125 operated a circuit is closed from battery, 130

through such locking winding by way of its right-hand armature and contact to a common lead indicated at 433, and to ground at the back contact and right-hand armature 5 of relay 311.

When the sequence switch 100 reaches position 7 with the thousands register in position 5, the following circuit is established from the source of 33-cycle alternating current.

- 10 which circuit may be traced from the generator 162 to the thousands register spring 165 in position 5, sequence switch contact 152 in position 7, brush 106, terminal 113, conductor 16, sequence switch contact 19 in position 11, brush 11, terminal 14, arm 302, conductor 304, relay 406, conductor 481, conductor 310, arm 301, terminal 13, brush 10, sequence switch contact 18 in position 11, conductor 17, terminal 112, brush 107, sequence contact 150 in position 7, to ground.
- 15 The relay 406 is energized in this circuit. At the same time a circuit is established for relay 312, which may be traced from battery, relay 312, arm 301, terminal 13, brush 10, sequence switch contact 18, position 11, conductor 17, terminal 112, brush 107, sequence switch contact 150 to ground. As the relay 312 is connected to the first six contacts swept over by arm 301, such relay will
- 20 be energized over contact 150 in positions 7, 9, 11, 13, 15 and 17 of sequence switch 100. The relay 312 closes at its armature and contact a circuit for the magnet 303, which magnet attracts its armature. As soon as
- 25 sequence switch 100 leaves position 7, the circuit previously traced being opened at contact 150, the relay 312 is deenergized, causing the deenergization of the magnet 303, which causes the switch 300 to step into its second position. The relay 406, however, is maintained energized over a locking circuit from battery through right-hand winding of relay 406, right armature and contact of such relay to conductor 433, and from
- 30 thence to the armature and back contact of relay 311, to ground.

When the sequence switch 100 reaches position 9 a circuit is closed from the source of 50-cycle alternating current, which circuit may be traced from the generator 161, hundreds register contact 166 in position 9, thousands register contact 167 in position 5, sequence switch contact 151 in position 9, brush 106, terminal 113, conductor 16, sequence switch contact 19 in position 11, brush 11, contact 14, arm 302 of switch 300 in position 2, conductor 305, relay 400, conductor 310, arm 301 in position 2, terminal 13, brush 10, sequence switch contact 18 in position 11, conductor 17, contact 112, brush 107, sequence switch spring 150 in position 9, to ground. The relay 400 is energized in this circuit. Relay 400 is locked at its right armature and contact. The relays 400 and 406 remain locked up until similar re-

lays in the tens and units indicators have been selected and in fact until the called subscriber has answered. The lamps of the indicator, however, are not displayed until the relay 313 is operated, as will be hereafter described. The relay 312 is also energized at this time through the switch contact 150 in position 9.

As soon as the sequence switch 100 leaves position 9, relay 312 is released, thereby de- 75 energizing magnet 303, and stepping the arms 301, 302 of the switch 300 into position 3.

When the sequence switch 100 reaches position 11 a circuit is established from the source of 66-cycle alternating current over the trunk line to the indicator, which circuit may be traced as follows: from the generator 160, 100's register contact 168 in position 9, sequence switch contact 152 in 80 position 11, brush 106, terminal 110, conductor 16, sequence switch contact 19 in position 11, brush 11, terminal 14, arm 302, conductor 306, relay 409, conductor 432, conductor 310, arm 301, terminal 13, brush 10, contact 18 in position 11, terminal 112, brush 107, sequence switch contact 150 in position 11 to ground. The relay 312 is also energized at this time through sequence switch contact 150. Relay 409 closes at its right 90 armature and contact a locking circuit for itself by way of the conductor 433. As soon as the sequence switch 100 leaves position 11, relay 312 is deenergized, thus permitting the magnet 303 to fall back, such magnet 100 having been energized in response to the energization of relay 312. Due to the deenergization of magnet 303 the switch arm 301 is stepped into its fourth position. When the sequence switch 100 moves into position 105 13, the 10's register being in position 3, a circuit is established from the source of sixteen cycle alternating current by way of the trunk line to the indicator, which circuit may be traced as follows: from the generator 163, 10's register contact 169 in position 3, sequence switch contact 152 in position 13, brush 106, terminal 113, conductor 16, sequence switch contact 19 in position 11, brush 11, terminal 14, arm 302, conductor 307, relay 421, conductor 434, conductor 310, arm 301, terminal 13, brush 10, sequence switch contact 18 in position 11, conductor 17, terminal 112, brush 107, sequence switch contact 150, in position 13 to ground. The 110 relay 312 is energized at this time through sequence switch contact 150 in position 13 and establishes a circuit from the magnet 303. The magnet 421 when energized in the circuit just traced closes a locking circuit 115 120 for itself by way of its right-hand armature and front contact and conductor 433 to ground. As soon as the sequence switch 100 leaves position 11, relay 312 becomes deenergized and consequently the magnet 303 is 130

deenergized, stepping the switch 300 into position 5.

When the sequence switch 100 reaches position 15, the 10's register being in position 3 and the units register in position 0, a circuit is established from a source of 33-cycle alternating current by way of a trunk line to the indicator, which circuit may be traced from generator 162, units register contact

- 10 170 in position 0, 10's register contact 171 in position 3, sequence switch contact 151 in position 15, brush 106, terminal 113, conductor 16, sequence switch contact 19 in position 11, brush 11, terminal 14, arm 302, conductor 15 308, relay 415, conductor 434, conductor 310, arm 301, terminal 13, brush 10, sequence switch contact 18 in position 11, conductor 17, terminal 112, brush 107, sequence switch contact 150 in position 15 to ground. Relay 20 312 is energized at this time through sequence switch contact 150 in position 15. When the sequence switch 100 leaves position 15, the relay 312 is deenergized, thus deenergizing the magnet 303, which steps the 25 arms of the switch 300 into position 6.

When the sequence switch 100 reaches position 17, a circuit is established over the trunk to the indicator which may be traced from the source of direct current 164, units

- 30 register spring 172 in position 0, sequence switch contact 152 in position 17, brush 106, terminal 113, conductor 16, sequence switch contact 19 in position 11, brush 11, terminal 14, arm 302, conductor 309, relay 427, to 35 ground. Relay 312 is also energized at this time over sequence switch contact 150 causing the energization of the magnet 303. Relay 427 closes at its right-hand armature and contact a locking circuit for itself by way 40 of the conductor 433. As soon as the sequence switch 100 leaves position 17, relay 312 is deenergized, deenergizing the magnet 303 and stepping the arms of the switch 300 into their seventh or through position. 45 When the sequence switch 100 reaches position 18, a sequence switch contact 176 is closed, establishing a circuit for the down-drive magnet of the cord finder which returns the cord finder to normal. As soon 50 as the cord finder reaches its normal position the off-normal spring 175 is closed, and sequence switch 100 is driven into its normal position over a circuit which may be traced from battery through the power magnet of 55 sequence switch 100, sequence switch contact 130 in position 18, off-normal spring 175 to ground. As sequence switch 100 passes position 17, relay 105 being still locked up, a circuit is established from battery, motor 60 magnet of sequence switch 7, sequence switch contact 8, position 11, sequence switch contact 143, position 17, front contact and right-hand armature of relay 105 to ground. Sequence switch 7, thereupon moves to position 65 12. The sender device having been discon-

nected from the trunk, may be used for association with another trunk or cord in setting up another number. As soon as the switch 300 reaches its seventh position or final position, a circuit is established for 70 the high-resistance winding of the relay 328, which circuit may be traced from battery through the winding of repeating coil 20, supervisory relay 21, contact 19 in position 12, brush 11, terminal 14, arm 302, winding 75 of the repeating coil 314, left-hand winding of relay 328, winding 315 of the repeating coil, arm 301, terminal 13, brush 10, contact 18 in position 12, winding 22 of the repeating coil to ground. Relay 328 being energized establishes a circuit from battery through the signal lamp 316, armature and contact of relay 328, lower armature and back contact of relay 317, relay 313 to ground. The energization of the relay 313 80 establishes circuits for the various lamps of the indicator as determined by the locked up indicator relays. Remembering that the relays 400, 406, 409, 415, 421 and 427 are locked up, the following circuits will be established. 85

From battery 440 through the left-hand armature and upper contact of relay 400, through the lamp 5 of the thousands indicator, left armature and front contact of relay 406, conductor 444 to armature and contact of relay 313 to ground. The No. 5 lamp of the thousands indicator is thus displayed. A circuit is also established from battery 440, left-hand armature and lower contact of relay 400, lamp 9, left-hand armature and front contact of relay 409 to conductor 444, armature and contact of relay 313 to ground. The No. 9 lamp of the hundreds indicator is thus displayed. A circuit is also established from battery 442, left armature and upper contact of relay 415, No. 3 lamp of the tens indicator, left armature and contact of relay 421 to conductor 444, armature and contact of relay 313 to ground. The No. 3 lamp of the tens indicator is thus 100 illuminated. A circuit is also established from battery 442, left-hand armature and lower contact of relay 415, No. 0 lamp of the units indicator, left armature and contact of relay 427, conductor 444, armature and contact of relay 313 to ground. 105

The operator having observed the number indicated by the indicator, inserts the plug 323, individual to the trunk indicated by the lamp 316, into the jack 324 of the desired 110 line. As soon as the plug is inserted in the jack after the usual preliminary testing, a circuit is established from battery 321 through lamp 316, relay 317, sleeve of the plug 323, sleeve of the jack 324, cutoff relay 322 to ground. The energization of the relay 317 over this circuit establishes a circuit for the relay 318, which may be traced from battery 327, armatures and back contacts of relays 320 and 311, relay 318, upper contact 115 120

125

130

and lower armature of relay 317, armature and contact of relay 328, through relay 317, sleeve of plug 323, sleeve of jack 324, cutoff relay 322 to ground. Battery 325 in this circuit shunts the battery 321 and extinguishes the lamp 316. Relay 317 in its lower armature opens the circuit previously traced for relay 313, causing the release of such relay and the consequent extinguishing of the indicator lamps. The relay 318 operating establishes the ringing circuit and connects a source of ringing current indicated at 326 to the called line. When the called subscriber answers, the ringing cut-off relay 320 and the supervisory relay 319 are energized. When the relay 320 is energized the shunt is removed from relay 311, permitting it to energize. Relay 311 at its right-hand contact and armature opens locking circuits of the selecting relays and also at its left armature and contact short-circuits relay 318. Relay 319 when operated cuts in the low-resistance winding of the relay 328, which lowers the resistances of the circuit previously traced for relay 328 so that the supervisory relay 21 of the A operator's position will operate and display the usual supervisory lamp, not shown, at such A operator's position. The operations of supervision and of disconnect will not be described as they form no part of the present invention.

What is claimed is:

1. In a telephone exchange system, an indicating arrangement comprising electro-responsive devices tuned to respond to currents of different frequency, a control circuit, manually controlled means for impressing combinations of currents of different frequencies on such control circuit to operate such electro-responsive devices in different combinations, indicating devices, a plurality of which are adapted to be simultaneously displayed in response to the operation of a particular combination of such electro-responsive devices.
2. In a telephone exchange system, a number indicating device, comprising a set of ten indicators for each digit of the maximum number it is desired to indicate, tuned electro-responsive devices less in number than said indicators, manually controlled means

for energizing such electro-responsive devices in various combinations, and a circuit for each indicator controlled by a pair of such electro-responsive devices.

3. In a telephone exchange system, an indicating arrangement comprising a plurality of digit indicators, each including a plurality of number indicators, a set of selecting relays individual to each digit indicator, additional sets of selecting relays common to a plurality of digit indicators, means for selectively energizing such selecting relays, and means controlled by a selecting relay of a set individual to a digit indicator and by a selecting relay of a set common to a plurality of digit indicators to cause the operation of a number indicator individual to such digit indicator.

4. In a telephone exchange system an indicating arrangement comprising a plurality of digit indicators, each comprising a plurality of number indicators, a plurality of sets of tuned electro-responsive devices for controlling such digit indicators, means for impressing currents of different frequencies on such control circuit to selectively operate such electro-responsive devices, and means also operated over the said control circuit to cause the successive association of such control circuit with a plurality of such sets of electro-responsive devices.

5. In a multi-office telephone exchange system, calling and called lines, a final connector operator's position, means for extending a calling line thereto over a trunk line, a device for indicating the number of a called line at said final connector operator's position, a plurality of sets of tuned selecting relays for controlling such indicating device, manually controlled means at another operator's position for impressing currents of different characteristics over one side of the trunk to selectively operate such selecting relays, and a step-by-step switch controlled over the other side of the trunk for successively associating such sets of selecting relays with the trunk.

In witness whereof, I hereunto subscribe my name this 13th day of November, A. D. 1916.

ALBEN E. LUNDELL.
